FOLLOWER FOR FILING COMPARTMENTS

Hans W. Regenhardt and George M. Beno,
Wooster, Ohio, assignors to Record Files, Inc.,
Wooster, Ohio, a corporation of Ohio

Application February 9, 1949, Serial No. 75,472

4 Claims. (Cl. 129—31)

1

This invention relates to followers for filing compartments and the like; particularly, improved followers of the general nature of those disclosed in Beno application Serial No. 686,661, filed July 27, 1946, Patent No. 2,501,491 for "Follower for Filing Compartments."

As in said copending application, one of the objects of the present invention is the provision of an improved follower which embodies a unitary locking mechanism to lock the follower firmly in any desired position in the filing compartment. Another object is the provision of such a follower which in large part can be manufactured by simple bending and forming operations. Another object is to provide such a follower which has ample strength to resist the forces imposed upon it. A further object is to provide a follower and locking device which can be readily installed in or removed from a filing compartment.

A further object of the invention is to provide a follower lending itself to one-hand operation, by which is meant the series of operations involved in insertion, placement and withdrawal of the follower; so that an amputee or a person whose other hand is holding material taken from or to be added to that in the compartment can perform unaided all of the acts necessary to introduce, locate, re-locate or remove the follower. A further object is to provide a normally retracted actuating member, such as a pry or lever, which forms part of the follower, is normally out of sight and out of the way, yet is instantly available to put its mechanical advantage to use to the end of facilitating one-hand operation as above described. A further object is to provide a follower that permits solid packing of the material in the compartment, particularly punch cards, without requiring the presence of space-wasting slack forward of the follower to leave room for pulling the follower toward the operator as an incident to re-location or removal.

Further objects and advantages of the invention will become apparent from the following description of a preferred form thereof, reference being made to the accompanying drawings in which Figure 1 is a perspective illustrating a follower embodying the invention installed in a compartment such as a drawer of a filing cabinet, parts of the compartment being broken away for convenience in illustration; Figure 2 is a side elevation, but with the operating lever in elevated position, of the assembly of Figure 1, the view being taken from the left as the assembly is therein illustrated; Figure 3 is a central

2

longitudinal section, corresponding to Figure 2, through the assembly of Figure 1; and Figure 4 is an end elevation, taken from the rear, showing the manner in which the follower is locked in position in the compartment, the front member of the compartment being omitted for clarity in illustration.

A preferred form of follower embodying the invention is shown in the drawing as installed in a compartment indicated in general at 10. The compartment, which in this example is a drawer of a filing cabinet, may be of more or less conventional construction comprising a suitable back member (not shown), a bottom portion 11, side walls 12, and a front member 13. The upper edges of the side walls 12 are provided with inwardly and downwardly extending flanges 14, thus providing inverted channels 15 extending along the upper edges of the side portions 12. This construction strengthens and stiffens the side portions and, as will appear below, permits the locking parts of the follower to engage flanges 14 at the base of channels 15 thereof.

Solidly packed between front member 13 and follower 17 is the material stored in the compartment, the same taking the form of punch cards 16.

The follower itself, indicated in general at 17, preferably is formed of sheet metal. It consists, along with other parts hereinafter described, of an upright web or body portion 19 disposed substantially but not necessarily precisely vertically in the compartment, a beaded top portion 20, a rearwardly extending bottom flange 21 having struck-down dimples 21a and 21b in contact with bottom portion 11 of the compartment, rearwardly extending side flanges 22 and 23, and, spot-welded to and preventing relative movement between side flanges 22 and 23, polygonal internal reinforcements 24 extending from just short of the bottom of lower flanges 22 to just short of the top of upper flanges 23. Flanges 22 form part of the locking mechanism, as will appear below, while flanges 23 are provided for strength and stiffness.

In addition, body portion 19 is further stiffened by spot-welding thereto a transversely extending sheet metal strap 25, the top portion 25a of which is reversely bent to provide an outwardly extending bead underlying and conforming to beaded top portion 20.

In fabricating follower 17, a single piece of sheet metal in the form of a stamping of suitable shape may be used to provide body portion 19, beaded top portion 20, bottom flange 21,

dimples 21a and 21b, and side flanges 22 and 23, the various flanges and other parts being struck up or struck down, as required, at appropriate stages in the sequence of operations. Side flanges 22 and 23 are so shaped, located and bent in the process of forming the follower as to be rather widely spaced from each other, as shown in elevation in Figure 2. Top portion 20 is cut away at its ends, as shown in Figures 1 and 4, to provide spaces between it and upper side flanges 23.

Bottom flange 21 is not rigidly affixed to but spaced very slightly from the bottom limits of lower side flanges 22; however, this is preferably accomplished not by cutting away lower side flanges 22, which, as shown in Figures 1 and 2, are squared off toward the bottoms thereof, but by making the included dihedral angle between bottom flange 21 and body portion 19 somewhat greater than 90°. This spacing, which is of varying width, largely disappears as a result of spring action when follower 17 is in its upright position. Its presence is indicated in exaggerated fashion in Figure 2, where, in the broken line position of follower 17, angle A appears as an obtuse angle.

From Figures 1 and 4 it will be noted that at their upper ends lower side flanges 22 are rather sharply angled to provide parallel but outwardly offset portions 26 having their edges 27 curved rearwardly and then abruptly downwardly from the highest portions 28 thereof, the latter being substantially, but not literally, in the plane of body portion 19. As shown best in Figures 2 and 3, the follower is so dimensioned that when it is in upright position with dimples 21a and 21b resting on the bottom 11 of the compartment, there is no appreciable clearance between the highest point 28 of offset portion 26 and the base (represented in Figure 2 by the broken horizontal line) of the channel within which it is disposed. The lack of clearance results in part from the spring action characterizing bottom flange 21, which tends to force points 28 of offset portions 26 into contact with the inwardly extending portions of inwardly and downwardly extending flanges 14.

With this arrangement, an external force applied to the follower from left to right as seen in Figures 2 and 3 will tend to rock follower 17 about edge 29 at the rear of bottom flange 21. As this edge is offset from points 28 on offset portions 26, the tendency will be to force points 28 into even closer engagement with flanges 14 at the base of the respective channels 15. In addition, the forces exerted by points 28 of offset portions 26 against the base of channels 15 react through bottom flange 21 of the follower against bottom portion 11 of the compartment. By this construction, follower 17 is locked securely in position against unintended rearward movement resulting from pressure exerted upon it by material supported by the front face of the follower.

The net effect, as a practical matter, is to prevent any possibility of accidental rearward displacement of follower 17. In consequence, follower 17 may be brought into very close contact with the material itself, as is desirable when the material nearly fills the compartment and follower 17 is toward the extreme rear thereof. In such case, particularly if the material in the compartment takes the form of punch cards 16, the solid mass of material backed by follower 17 will of course preclude the possibility of opposite or forward movement of the follower.

By the same token, however, the possibility of removing follower 17 by tilting it forward, to that

end pivoting it about the base of body portion 19, is precluded by the presence of the material backed by the follower.

To cope with this state of affairs, a metal pry 30 having rearwardly turned ends 30a and 30b is mounted in a flared metal retainer 31 that is spot-welded on or otherwise made fast to strap 25. Pry 30 may take any suitable form but conveniently may be of the nature of a retractable rod or bar having its ends 30a and 30b bent at right angles to permit them to serve as holds or stops. Retainer 31 is so shaped as to provide therein a passageway 33 within which pry 30 may, as desired, be pulled up to functioning position (Figures 2 and 3) or permitted to drop down out of sight into non-functioning position (Figures 1 and 4). In order that pry 30 may clear top portion 20 of follower 17, which, reinforced by top portion 25a of strap 25, serves as a fulcrum for pry 30, retainer 31 is flared outwardly as shown in Figures 1 and 3.

In use, the person seeking to re-locate or remove follower 17 grasps pry 30 at or near hold 30a, lifts it up at the angle required to clear top portion 25a of strap 25, and, using one hand, pulls it forward; i. e., counterclockwise as seen in Figures 2 and 3. A forwardly acting force so applied to the upper end of pry 30 manifests itself as a rearwardly acting force against retainer 31 toward the lower end thereof, where stop 30b or pry 30 abuts retainer 31. Pivoting about the horizontal top edge of the solid mass of material made up of punch cards 16, follower 17 is thereby dislocated as indicated in broken lines in Figure 2, top portion 20 thereof tending to remain in sliding contact with punch cards 16 and bottom flange 21 assuming an inclined position in sliding contact with the bottom portion 11 of the compartment. The presence of dimples 21a and 21b on bottom flange 21 assists in the release of the latter notwithstanding the spring action previously mentioned, this because the surface contact and the frictional resistance arising out of surface contact between bottom flange 21 and bottom portion 11 of the compartment is thereby held to a minimum.

Thereafter, rearward movement of follower 17 in the manner and direction so initiated is continued until after clearance permitting re-location or removal of follower 17 has been established between flanges 14 and offset portions 26.

If, for the purpose of removing follower 17, such movement is continued until follower 17 assumes a substantially horizontal position, pry 30 is allowed, once clearance has been established, to drop into its retracted position, after which it is a simple matter to push follower 17 in a rearward direction until top portion 20 thereof moves out of contact with punch cards 16. At this stage, follower 17 may be bodily removed merely by turning it out of transverse and into an oblique position with respect to the compartment until it can be lifted out without having offset portions 26 re-engage flanges 14.

Installation of the follower in a compartment is carried out by inserting the follower in an oblique position, turning it until it is normal to side walls 12 of the compartment, and then rocking it into substantially vertical position with offset portions 26 disposed within channels 15.

As noted, lower flanges 22 on the sides of follower 17 are for the most part out of engagement with bottom flange 21. Thus bottom flange 21 and lower flanges 22 do not reinforce each other. It is to stiffen and prevent angular separation of

side flanges 22 and 23 that polygonal internal reinforcements 24 are provided, such reinforcement being doubly desirable because of the force exerted by pry 30 against body portion 19 of follower 17. A further measure of reinforcement is provided by transversely extending strap 25, which is in contact throughout its length with body portion 19 and at its ends with upper flanges 23, particularly toward the top thereof, where top portion 25a of strap 25 abuts polygonal reinforcements 24. Thus is provided a light, sturdy follower which makes possible the attainment of the objects heretofore noted.

Various changes and modifications may be made in the invention without departing from the spirit and scope thereof. It is therefore to be understood that the patent is not limited to the preferred form of invention. On the contrary, it is intended that the patent shall cover, by suitable expression in the appended claims, whatever features of patentable novelty reside in the invention.

What is claimed is:

1. A follower for a compartment used for filing, storage or the like comprising an upstanding sheet metal web having a beaded top portion; a transversely extending sheet metal strap fastened to the web, said strap having a reversely-bent portion underlying and conforming in shape to the beaded top portion of the web; a metal retainer mounted on said strap; a longitudinally movable metal lever carried by said retainer, said lever being movable independently of the follower and adapted to bear against the beaded top portion of the web; upper and lower side flanges integral with the web, said lower side flanges

25

35

having locking means associated therewith; a sheet-metal reinforcement connecting the upper and lower side flanges at each end of the web, said reinforcement extending from a point short of the bottom of the lower flange to a point short of the top of the upper flange; and, cooperating to lock the lower side flanges in fixed position, a bottom flange integral with and projecting from the web in such manner as to define an angle of a magnitude greater than 90°.

5 10 15 20 25

2. A follower as in claim 1 in which the bottom flange is spaced from the bottom limits of the lower side flanges.

3. A follower as in claim 1 in which the bottom flange has a limited amount of freedom of movement relative to the web of a kind such as to impart a spring action to the bottom flange.

4. A follower as in claim 1 in which the bottom flange is provided with a plurality of integrally formed projections extending downward from the lower face of the bottom flange.
